ORDNANCE FIRING MECHANISM.

1,360,195.

Specification of Letters Patent. Patented Nov. 23, 1920.

Application filed May 29, 1918. Serial No. 237,363.

To all whom it may concern:

Be it known that we, Sir ARTHUR TREVOR DAWSON, knight, and Sir GEORGE THOMAS BUCKHAM, knight, both subjects of the King of Great Britain, residing at Vickers House, Broadway, Westminster, in the county of London, England, have invented certain new and useful Improvements in or Relating to Ordnance Firing Mechanism, of which the following is a specification.

This invention relates to firing mechanism for ordnance of the kind having a sliding lock frame movable transversely to the axis of the gun in a box slide attached to the rear end of the axial vent bolt.

According to the invention the lock frame carries a striker of the hammer type pivoted to move in a plane transverse to the path of travel of the lock frame, this arrangement enabling the hammer to be cocked by a lanyard without possibility of the lock frame being displaced from its closed position by the pull of the lanyard and obviating the necessity for a locking pin to prevent this movement; it also enables the overall length of the lock to be reduced to a minimum. Carried in the lock frame is the firing spring and plunger, the latter being preferably so arranged as to engage with projections disposed on the hammer one on each side of the hammer pivot; this arrangement gives a balancing effect to the hammer so as to cause it to be slightly withdrawn to a retracted position after firing, the momentum of the rapidly moving hammer when firing being more than sufficient to overcome the slight initial spring pressure necessary for retraction.

In order that the said invention may be clearly understood and readily carried into effect we will describe the same more fully with reference to the accompanying drawings in which:—

Figure 1 is a rear elevation showing the improved lock mechanism in position on the gun, the lock frame in this figure being adapted to move in a path at an angle to the vertical.

Fig. 2 is a rear elevation of the improved lock mechanism, the lock frame in this case being adapted to move in a vertical path.

Fig. 3 is a plan of Fig. 2.

Fig. 4 is a section taken approximately on the line 4, 4 of Fig. 2.

Fig. 5 is a view similar to Fig. 4 but show-

ing the hammer in the rearmost position; and

Fig. 6 is a vertical section viewed in the opposite direction from that of Fig. 2 (viz., from the muzzle end of the gun) showing a detail hereinafter referred to.

Fig. 7 is a section taken approximately on the line 7—7 of Fig. 2, and

Fig. 8 is a section taken approximately on the line 8—8 of Fig. 2.

A (Fig. 1) is the carrier, B the box slide, and C the axial vent bolt to which the box slide is connected by a continuous screw thread or by interrupted collars in the usual manner. D is the lock frame movable in an upward direction on the box slide to expose the primer chamber in the axial vent bolt, D' is a lock frame operating handle pivoted at d' to a bracket D^x attached to the lock frame, and d' (Fig. 6) is a hook-shaped projection on the handle D' for engaging in a recess b' in the box slide to hold the lock frame in the closed position. E is the firing hammer pivoted at e to the lock frame so as to move in a plane at right angles to the path of travel of the lock frame, and E³ is a projection on the hammer E, this projection having an inclined surface with which an extension D^x of the handle D' engages to slightly retract the hammer when the handle is rocked about its pivot to disengage the projection d' from its recess b' prior to the movement of the lock frame to the open position, this retraction of the hammer being for the purpose of bringing its striking point clear of the box slide during the movement of the lock frame. E' is the firing spring and e' is its plunger engaging with projections e^x, e'^x one on each side of the hammer pivot e. The lock frame D is formed with longitudinal grooves adapted to engage with fins B², B² on the box slide B and also with fins C², C² on the axial vent bolt, the latter fins forming continuations of the fins B², B²; this arrangement is more fully described in the specification of our Patent No. 1,337,308. In this manner the lock frame serves to retain the box slide in its correct position on the axial vent bolt.

The spring plunger e' carried by the lock frame and serving to move the firing hammer to fire the gun, is so arranged in relation to the projections e^x, e'^x on the hammer, that when the parts are in the position shown by Fig. 4, the hammer is retracted. 105

When the hammer is moved rearward, the forward projection e^x on the hammer displaces the plunger e' to energize the spring E' (see Fig. 5) and when the hammer is then released, it flies forward under the influence of the spring acting on the projection e^x , the momentum of the hammer carrying it past the position shown by Fig. 4 to bring the rear projection e'^x against the 10 spring plunger; the subsequent reaction of the spring operating upon the hammer through the projection e'^x then causes the hammer to be slightly retracted into the position of equilibrium shown by Fig. 4.

15 A projection E^4 extending to the rear of the hammer serves to receive the lanyard hook which is retained in position by means of a lanyard guard e^4 disposed in the hammer and mounted on the pivot pin e of the 20 hammer. The lanyard guard is moved into the position shown by Fig. 5 by the contact of a face e^5 on the guard with a stop e^{5x} on the lock frame, thereby freeing the lanyard and releasing the hammer; this arrangement 25 constituting firing mechanism of the slip-lock hammer type. The rearward movement of the hammer is limited by a stop e^6 and the hammer may have a projection E^6 (Fig. 5) for the purpose of holding the 30 hammer in the retracted position while the lock is sliding in the box slide. When the lock frame is arranged to move at an inclination as shown by Fig. 1, a fairlead E^6 is provided for the lanyard so that the inner 35 portion of the lanyard lies at the required angle.

What we claim and desire to secure by Letters Patent of the United States is:—

1. In ordnance lock mechanism, the combination with the wedge or lock frame and the receiver or box slide in which the lock frame moves, of a firing mechanism of the slip-lock hammer type, the hammer being pivoted to said lock frame so as to move in a plane transverse to the path of travel of the lock frame, an operating handle for the lock frame and means whereby movement of said handle preparatory to displacing the lock frame to the open position causes the 50 hammer to be retracted.

2. In ordnance lock mechanism, the combination with the wedge or lock frame and the receiver or box slide in which the lock frame moves, of a firing hammer pivoted 55 to said lock frame so as to move in a plane transverse to the path of travel of the lock frame, an operating handle on the lock frame and means whereby movement of said handle preparatory to displacing the lock frame to the open position causes the 60 hammer to be retracted.

3. In ordnance lock mechanism, the combination with the wedge or lock frame and the receiver or box slide in which the lock 65 frame moves, of a firing hammer pivoted

to said lock frame so as to move in a plane transverse to the path of travel of the lock frame and a spring adapted to operate upon the hammer to one side or the other of its pivot according to the position of the 70 hammer.

4. In ordnance lock mechanism, the combination with the wedge or lock frame and the receiver or box slide in which the lock frame moves, of a firing hammer pivoted to 75 said lock frame so as to move in a plane transverse to the path of travel of the lock frame and provided with projections one on each side of the pivotal axis of the hammer and a spring plunger with which one or 80 the other or both of said projections are adapted to engage according to the position of the hammer, the hammer being in a retracted position of equilibrium when both the projections are engaging with the 85 plunger.

5. In ordnance lock mechanism, the combination with the wedge or lock frame and the receiver or box slide in which the lock frame moves, of a firing hammer pivoted to 90 said lock frame so as to move in a plane transverse to the path of travel of the lock frame and provided with projections one on each side of the pivotal axis of the hammer, a firing spring for said hammer and a plunger subject to the influence of said spring with which plunger one or the other or both of said projections are adapted to engage according to the position of the hammer, the 95 hammer being in a retracted position of equilibrium when both the projections are engaging with the plunger.

6. In ordnance lock mechanism, the combination with the wedge or lock frame and the receiver or box slide in which the lock 105 frame moves, of firing mechanism of the slip-lock hammer type, the hammer being pivoted to said lock frame so as to move in a plane transverse to the path of travel of the lock frame, an operating handle on the 110 lock frame and means whereby movement of said handle preparatory to displacing the lock frame to the open position causes the hammer to be retracted.

7. In ordnance lock mechanism, the combination with the wedge or lock frame and the receiver or box slide in which the lock frame moves, of firing mechanism of the slip-lock hammer type the hammer being pivoted to said lock frame so as to move in 120 a plane transverse to the path of travel of the lock frame and a spring adapted to operate upon the hammer to one side or the other of its pivot according to the position of the hammer.

In testimony whereof we affix our signatures.

ARTHUR TREVOR DAWSON.
GEORGE THOMAS BUCKHAM.
